UNITED STATES PATENT OFFICE.

SAMUEL A. NEIDICH, OF EDGEWATER PARK, NEW JERSEY.

FILAMENT-DRYING APPARATUS.

Application filed June 5, 1926. Serial No. 113,869.

My invention relates to the manufacture of filaments from viscose (cellulose sulphocarbonate or thiocarbonate) and may be employed with particular advantage in the production of coarse filaments such as artificial horse hair.

Liquid viscose may be coagulated or precipitated to form a gelatinous semi-solid cellulose hydrate complex by progressively extruding a stream of it into a heated atmosphere or into an aqueous solution containing a suitable acid, for instance, sulphuric or hydrochloric acid, or containing an acid salt such as sodium bi-sulphite or ammonium chloride either with or without neutral salts or dehydrators, or both.

Such colloid filaments are amorphous and more or less soft and impressionable, in accordance with the nature of the coagulating medium to which they have been subjected; for instance, an acid coagulating medium has a greater initial hardening effect than a salt coagulating medium. When soft, such a filament may be deformed by contact with itself in successive convolutions and have slight indentations thus formed therein which detract from its commercial value when dried, because such deformations reflect light and are noticeable in comparison with the portions of the filament which are smoothly cylindrical and uniformly lustrous. Consequently, when it is desired to form such filaments of uniform cross section free from indentations it is undesirable to wind them in the usual way directly upon bobbins or other similar holders because if wound on such containers the stresses from the shrinkage in drying produces detrimental marks on the under layers.

Therefore, I devised a filament drying apparatus which is the subject matter of Letters Patent of the United States 1,568,686 granted to me January 5, 1926; including a reel and means for directing such a soft filament singly in a helically spaced coil thereon; said reel being of such extent that the initial end of the filament became dried before the final end thereof was wound upon the reel; so that the operation of unwinding each piece of filament might be begun as soon as the winding operation thereof was completed and, the operation of unwinding a preceding dried filament might be effected simultaneously with the operation of winding a succeeding wet filament upon the same reel; such operation being practically continuous, under normal conditions, as it is only momen-

tarily interrupted while a filled bobbin is being removed and replaced by an empty one or if the filament breaks, the latter interruption being only long enough to permit the operator to connect the broken ends of the filament. Although such construction and arrangement are efficient for producing filaments which are smoothly continuous without detrimental indentations; the drying operations effected thereby become an undesirable limiting factor in the quantity production of the dried filament. For instance, with a reel of such size as to hold five thousand yards of a filament thus wound singly; only seven pounds of such filament may be dried in twenty-four consecutive hours.

Therefore, the object and effect of my present invention is to utilize reeling mechanism of the general character disclosed in said Letters Patent to effect the drying of a larger quantity of filaments in a given time than is possible with the means and methods described in said Letters Patent. By the means and methods described herein; twenty pounds of such filaments may be dried in twenty-four hours by the use of a reel of the same capacity heretofore capable of drying seven pounds.

In accordance with my present invention; I precipitate the extruded viscose filaments with coagulating means capable of imparting the greatest possible initial hardness to the filaments. Then, instead of winding filaments singly, I aggregate such a plurality of filaments as to form a massive skein, which, when wound upon the reel, forms a band say three inches wide. Such a skein is helically wound upon the reel from end to end thereof until the reel is charged with a mass of filament several inches thick. The reel being continuously rotated in the same direction until the entire mass of filaments are dried; the filaments may then be unwound by reversing the direction of rotation of the reel and without tangling the filaments.

My invention includes the various novel features of construction and arrangement hereinafter more definitely specified.

In said drawings; Fig. I is a diagrammatic end view of a filament drying apparatus conveniently embodying my improvement.

Fig. II is a diagrammatic side elevation of the apparatus shown in Fig. I.

In said figures; 1 indicates a skein composed of an aggregate of single filaments of gelatinous semi-solid cellulose hydrate

formed by extruding viscose into a coagulating medium and still moist with the water and other liquid contents of the original viscose and the coagulating medium. For instance, each of said filaments may be adapted to form a four hundred fifty denier artificial horse hair and is about twice the diameter when moist that it will be when it is dried. The number of said filaments in said skein is such that the skein spreads into a band about three inches wide as it passes over the guide roller 2 and on to the reel 3. Said reel comprises opposite end frames 5 rigidly mounted upon the shaft 6 and rigidly connected by the circumferential series of slats 8. Said shaft 6 of the open reel thus formed is so journaled as to be freely rotated by the electric motor 10 which has the pulley 11 driving the belt 12 extending around the distal end wheel frame 5 as indicated in Fig. I, and may be reversed by the switch 13. The normal speed of rotation of said reel is so great that it would continue to turn to an undesirable extent, after the operation of said motor is stopped, unless means be provided to check it. Therefore, I prefer to provide a brake band 14 which is fastened at its rear end to the support 15, extends thence over the circumference of one of said 30 wheel end frames 5 and is connected with the pedal lever 16 so that the operator by depressing said lever may frictionally engage said brake band with the reel to stop the rotation of the latter.

Said guide roller 2 is movable back and forth throughout the length of said reel upon which the filament is to be wound, so as to direct said skein 1 in helical convolutions upon said reel, which is thus charged with a mass of filaments several inches thick, as indicated. Whereupon, the last end of said skein may be secured to said reel and the latter continuously rotated, in one direction, at high speed; say with a circumferential speed of four hundred yards per minute, until the filament is dried. Thereupon, the rotation of the reel may be stopped and the ends of the individual filaments be connected to respective bobbins 18 which may be simultaneously but independently rotated by any suitable means, for instance, belts 19, so that said filaments are separately but simultaneously wound upon said bobbins as they are unwound from said reel which then turns in the opposite direction to that in which it was rotated when said skein was wound thereon.

I find it possible to repeat the complete cycle of operation aforesaid eighteen times in twenty-four hours thus drying an average of twenty pounds per day on each such reel. I find it convenient to use a viscose containing twelve percent of cellulose in hydrated form and, as above indicated; the drying operation aforesaid causes the initially moist filaments to shrink to about fifty percent of

their original volume. If the filaments were initially wound upon individual bobbins; such shrinkage would cause detrimental marking of the filaments by the pressure of the successive convolutions of the filaments upon each other. However, the stresses of such shrinkage are so distributed and dissipated in the mass of filaments drying upon the reel in a skein as aforesaid that such detrimental marks are avoided. 75

Although I have found it convenient to employ an embodiment of my invention as above described; I do not desire to limit myself to the precise details of construction and arrangement herein set forth, as the essential 80 feature of my invention is the winding of a large number of filaments together and simultaneously in helically axially spaced convolutions, in which they are exposed to a drying atmosphere, and thereafter unwinding said filaments simultaneously but separately, so that they are not tangled together, and it is obvious that various modifications may be made in the apparatus without departing from the essential features of my 90 invention as defined in the appended claims. 95

I claim:

1. In filament drying apparatus; the combination with an open reel; of means arranged to rotate said reel selectively in opposite directions; means arranged to singly direct and assemble a plurality of wet filaments in a single skein or band upon said reel, at one end thereof, and distribute the same in helical convolutions by reciprocation parallel with the axis of said reel, while rotating said reel in one direction; means arranged to rotate said reel at increased speed when charged, to dry said filaments; and means arranged to withdraw the dried filaments, in reverse direction, singly and separately but simultaneously from said reel, and contemporaneously wind each of said filaments singly and separately upon respective bobbins while rotating said reel in the opposite direction. 105

2. In filament drying apparatus; the combination with an open reel; of means arranged to rotate said reel selectively in opposite directions; means arranged to singly direct and assemble a plurality of wet filaments in a single skein or band upon said reel, at one end thereof, and distribute the same in helical convolutions while rotating said reel in one direction, and including a guide arranged to reciprocate parallel with the axis of said reel; means arranged to rotate said reel at increased speed when charged, to dry said filaments; and means arranged to withdraw the dried filaments, in reverse direction, singly and separately but simultaneously from said reel and contemporaneously wind each of said filaments singly and separately upon respective bobbins while rotating said reel in the opposite direction. 115 120 125 130

3. In filament drying apparatus; the combination with an open reel; of means arranged to rotate said reel selectively in opposite directions; means arranged to singly direct and assemble a plurality of wet filaments in a single skein or band upon said reel, at one end thereof, and distribute the same in helical convolutions while rotating said reel in one direction; means arranged to rotate said reel when charged, to dry said filaments; and means arranged to withdraw the dried filaments, in reverse direction, singly and separately but simultaneously from said reel and contemporaneously wind each of said filaments singly and separately while rotating said reel in the opposite direction.
